METHOD OF MOLDING CONCRETE STRUCTURES BY MEANS OF COLLAPSIBLE TUBULAR FORMS

Michael O'Flaherty, Ontario, Calif.

Application December 18, 1948, Serial No. 66,011

1 Claim. (Cl. 25—155)

1

This invention relates to a method of providing forms for concrete structures, it being an object of the invention to provide a method of molding concrete structures utilizing a disposable form which may be manufactured in relatively long lengths of flexible tubing capable of being rolled up for convenient shipping, storing and handling.

It is another object of the invention to provide a method of molding concrete structures utilizing a disposable concrete form so constructed that it may be carried to the job in long lengths and in rolled up form, and there cut into shorter lengths as used.

A further object is to provide a method of molding concrete structures utilizing a disposable concrete form of the character referred to on which linear length indicia are displayed to enable a workman to readily cut the length into precise shorter individual lengths.

It is also an object to provide a novel method of providing forms for concrete structures.

Other objects and advantages will appear from the following detailed description of a presently preferred embodiment of the invention, for which purpose I shall refer to the accompanying drawings, wherein:

Fig. 1 is a side elevational view of a relatively long length of tubing formed in accordance with my invention;

Fig. 2 is a section taken on line 2—2 of Fig. 1;

Fig. 3 is a section showing the device of Fig. 1 in flattened form;

Fig. 4 is an enlarged side elevational view of an individual form cut from the length of tubing of Fig. 1;

Fig. 5 is an enlarged sectional view of an individual form filled with reinforced concrete mix;

Fig. 6 is a view of a length of form material shown in rolled up form;

Fig. 7 is a side elevational view of a modified use of my invention; and

Fig. 8 is a view, partly in section and partly in side elevation, of a further modification.

It will be understood, of course, that within the purview of the accompanying claim I contemplate that my invention may be embodied in other modified specific forms.

Referring now to the drawings, I show in Fig. 1 a relatively long length 5 of flexible material, such as ordinary tarpaper or the like, formed into

2

tubular form and having displayed lengthwise thereof along at least one side a plurality of indicia 6 indicating measurements in feet, inches and fractions of inches.

5 In forming the lengths 5 I use rectangular sheets of tarpaper, the side edges of the sheet being overlapped and cemented together as shown at 7 in Fig. 2. After thus being formed into tubular shape, the length 5 is flattened, as shown in Fig. 3, and rolled up longitudinally, as shown in Fig. 6.

Thus, in use of the forms on the job, the workman, after using a transit, for instance, in determining that, for a given spot, a form of a given 15 height or length from the foundation is desired, may conveniently cut an appropriate length from the roll 5 and thus provide an individual tubular form 8 of the desired length, place it against the foundation F and pour the wet concrete mix into 20 it. The ends of the form 8 are open so that the mix may be poured in from the top end and it may bind to the foundation through the bottom end. After the mix sets and hardens in the form, the form may be torn therefrom and destroyed, 25 being made of a very cheap and disposable material. I prefer to use tarpaper for the form because it is economical and retains the water in the mix during the hardening and setting stage.

It is, of course, possible to use my form for 30 providing a reinforced concrete construction, such as shown in Fig. 5. Here I first embed the lower ends of metal reinforcing rods 9 in the foundation F and then apply the tubular form 8 thereover, after which the concrete mix M is 35 poured into the form around the reinforcing rods.

From the foregoing it will be apparent that my form is adaptable for structures of various sorts in addition to forming upright posts or piers, as shown in Figs. 1-6. It may be used, for instance, 40 to provide foundations or supports as shown in Fig. 7, by laying some of the preformed structures 8a horizontally and sandwiching therebetween crosswise disposed preformed structures 8b.

In Fig. 8 I show a further variational form in 45 which my invention may be carried out. Here I mount the flexible tube or sleeve 8c in a wire mesh sheathing 10 made of such pliant wire mesh as "chicken wire"; the concrete mix M being poured in the tube 8c. This form is highly useful for 50 columns and posts which must be plastered, since

the tarpaper sleeve prevents chemicals from seeping out into and discoloring the applied plaster. Such forms may be initially made in relatively long lengths such as shown in Fig. 1, and subsequently cut into individual forms of shorter length after being transported to the job in flattened and rolled up form.

I claim:

The method of providing forms for concrete structures comprising forming a relatively long length of material into tubular form, flattening the same, determining the height of desired individual structures, sequentially cutting, from the relatively long length of flattened material, relatively shorter lengths corresponding with the

height of the said individual structures, restoring said shorter lengths into tubular form, positioning said shorter lengths upon a foundation and filling them with concrete mix.

MICHAEL O'FLAHERTY.
